DESIGN FOR A NECKLACE

Claude Arpels, New York, N. Y.

Application October 10, 1946, Serial No. 133,873

Term of patent 3½ years

(Cl. D45—16)

To all whom it may concern:

Be it known that I, Claude Arpels, a citizen of the United States of America, residing in New York, county of New York, and State of New York, have invented a new, original, and ornamental Design for a Necklace, of which the following is a specification, reference being had to the accompanying drawing, forming part thereof.

Fig. 1, is a plan view of a necklace showing my new design.

Fig. 2, is an edge view in open position.

I claim:

The ornamental design for a necklace, substantially as shown.

CLAUDE ARPELS.
